UNITED STATES PATENT OFFICE.

THOMAS A. PATTERSON, OF CLINTONVILLE, WISCONSIN.

DRIVING MECHANISM.

Application filed November 10, 1924. Serial No. 748,934.

To all whom it may concern:

- Be it known that I, THOMAS A. PATTERSON, a citizen of the United States, and resident of Clintonville, in the county of Waupaca and State of Wisconsin, have invented certain new and useful Improvements in Driving Mechanism; and I do hereby declare that the following is a full, clear, and exact description thereof.
- 10 This invention relates to improvements in driving mechanism and while it is applicable to a large number of different types of driving mechanism it is primarily intended for a driving mechanism actuated from the transmission of an automobile and cooperating therewith to transmit power to other portions of the automobile, such for example the speedometer.
- 15 Objects of this invention are to provide a driving mechanism which may be applied to existing types of automobiles to adapt the machine for a speedometer drive directly from the transmission, in which a portion of the driving mechanism is held in place by means already on the transmission, and in which a very simple means has been provided for taking up wear or backlash and guarding against slackness or looseness in the mechanism.
- 20 Further objects are to provide driving mechanism which requires a very small alteration in the transmission to permit its use, which is very easily assembled, and which may be applied to the transmission by an unskilled operator without requiring the services of a machinist and without requiring special tools.
- 25 Further objects are to provide a driving mechanism which is both inexpensive to make and inexpensive to keep in repair even after great length of service, and which is strong, simple and durable.
- 30 An embodiment of the invention is shown in the accompanying drawings, in which:—
- 35 Figure 1 is a fragmentary view of a transmission case showing the driving mechanism in place.
- 40 Figure 2 is a sectional view on the line 2—2 of Figure 1.
- 45 Figure 3 is a sectional view on the line 3—3 of Figure 2, such view omitting the transmission case for the sake of clearness.
- 50 Figure 4 is a sectional view through the driving ring gear.
- 55 Figure 5 is a view of the driving gear as it appears detached from the mechanism.
- For the purpose of illustration, the device has been shown applied to the transmission of a certain make of car, but it is obvious that it may be applied to other types of transmission and to other types of mechanism. However, to simplify the disclosure, the description will be confined to the exact showing although, as stated, it is to be understood that this disclosure is one of many embodiments of the invention.
- Referring to the drawings, it will be seen that a transmission casing 1 such as employed in cars commercially known as Fords is disclosed. This transmission casing 70 houses the driving shaft 2, the clutch 3, the clutch control collar 4 and the clutch spring 5, together with other mechanism omitted for the sake of clearness. This transmission casing is provided with a cover plate. However in practising this invention the cover plate is replaced by the specially formed cover plate 6 (see Figures 1, 2 and 3.) This cover plate is held in place by the usual screws 7, suitable apertures being provided for such screws. It is to be noted, however, that the upper right hand aperture 8 is merely a circular hole and the entire cover plate is adapted to pivot slightly about the corresponding screw 7. All of the other apertures, as indicated at 9, are slotted so as to accommodate this pivotal motion, for a purpose hereinafter to be described.
- 80 This cover plate is provided with a channel like depression 10 which is equipped with a slanting bottom wall and with a transverse end wall 11. This end wall is apertured and receives the bearing 12 for the flexible shaft, such bearing being of the conventional type and provided with a collar 13 adapted to be clamped against the wall 11 by means of the clamping nut 14, as shown in Figure 2. It is to be noted that the plate 6 may be stamped from sheet metal in a very simple and cheap manner, and that due to the angularly offset wall 11, it is possible to readily clamp the sleeve or bearing directly to such offset wall by means of the nut 14, thus producing a very cheap, simple, and easily assembled construction.
- 85 90 95 100 105 110
- The flexible shaft is, of course, carried within a housing 15 in the usual manner and such flexible shaft is provided at its lowermost end with a spiral pinion 16. This spiral pinion is preferably formed of fiber, rawhide, phenol condensation products or of other similar material, although in cer-

tain cases it may be made of metal. It has been found, however, in extensive tests that a spiral pinion made of the material such as described, is substantially noiseless and also 5 has a very long life. The pinion 16, as is clearly shown in Figure 3, is held in place by means of a nut 17, such nut being locked against inadvertent rotation in any suitable manner, as by means of a split pin 19 and notches for instance, although such conventional locking means has been omitted from the drawing as they are well known. The purpose of providing the nut 17 is to 15 permit the ready renewal of the pinion 16, although from actual tests the pinion will last for an indefinite period.

The remaining portion of the drive mechanism comprises a ring gear 18 which is provided with spiral teeth or threads meshing with the teeth of the pinion 16. The pitch of the respective teeth is preferably so arranged that the pinion runs at a relatively low rate of speed under normally operating conditions.

20 The ring gear 18, as will be seen from Figures 4 and 5, is provided with a rearwardly extending cylindrical portion 19 which is provided with a plurality of cut-out portions 20. This cylindrical part 19 of the ring gear is provided with an inwardly extending flange 21. It is to be particularly noted that the ring gear 18 is formed in two parts, and the adjacent ends of the parts are in each case joined by 25 means of a tongue 22 which extends between a pair of tongues 23. These pins are all apertured and a split pin 24 is passed through the apertures to thus lock the component parts of the ring gear rigidly together.

In applying the device to existing types of automobiles, it is merely necessary to 30 pry the rear end of the spring 5 away from the flange of the clutch spring support 25 (see Figure 2.) This may be readily done by means of an ordinary screw driver, for instance. Thereafter, one-half of the split ring gear is slipped into place with one of the apertures 24 accommodating the screw 35 driver, and this portion of the gear is pressed downwardly until the flange 21 thereof is located between the rear end of the spring 5 and the flange 25 of the fixed collar or spring support, as shown in Figure 2. Thereafter, the drive shaft 2 is turned half way over and the other half of the ring gear 18 is slipped into position 40 in a similar manner. The split pins 24 are then passed through the apertured lugs 22 and 23, as shown in Figure 4, thus locking the component parts of the ring gear rigidly together.

45 It is to be particularly noted that the clutch spring 5 fits beneath the major portion of the ring gear and that its rear end

holds the flange 21 of the ring gear tightly bound against the flange 25 of the fixed collar or clutch spring support, as shown in Figure 2.

It will be seen, therefore, that the ring 70 gear may be applied by anyone without requiring either the use of special tools or the services of a machinist, and that after such ring gear has been placed, as described, that it will be most rigidly held in place by 75 the usual clutch spring 5.

Thereafter, the cover plate 6 is positioned and secured by means of the screws 7 with the pinion 16 meshing with the ring gear 18. It will be seen that the most exact adjustment may be readily secured by rocking the plate about the pivot screw which passes through the aperture 8 in the upper right hand corner of the plate 6 (see Figure 1). The gears may therefore be correctly 85 adjusted for perfect intermeshing.

Further, it is to be noted that any wear that may take place between the gears may be most readily cared for by a similar adjustment of the plate 6.

90 It will thus be seen that a drive mechanism has been provided which is of extreme simplicity, of rugged construction, and which may be most accurately and easily applied to existing types of machines 95 with a minimum of change.

Although this invention has been described in considerable detail, it is to be understood that the invention may be variously embodied and is, therefore, to be 100 limited only as claimed.

I claim:

1. In an automobile the combination of a drive shaft having a clutch spring thereon, a support against which said spring 105 normally bears, a split ring gear surrounding said shaft and clamped between said support and said spring, a housing for said drive shaft, said housing having an aperture therethrough, a plate adapted to close 110 said aperture and having a bearing thereon, a driven shaft carried within said bearing, and a pinion carried by said shaft and adapted to mesh with said gear when said plate is in position, said plate having apertures 115 therein adapted to receive securing means for attaching it to said casing, certain of said apertures being elongated to permit adjustment of said plate.

2. In an automobile the combination of a 120 transmission casing having an aperture therein, a driving shaft mounted within said casing, a split ring helical gear adapted for attachment to said shaft, a cover plate adapted to cover the opening in said casing 125 and having marginally located apertures, securing means extending through said apertures and into said casing, certain of said apertures being elongated for adjustment of said plate, a bearing clamped 130

to said plate, a driven shaft carried by said bearing and projecting through said plate, a helical pinion carried by the lower end of said driven shaft and adapted to mesh with said ring gear.

3. In an automobile the combination of a casing having an aperture therein, a driving shaft mounted within said casing, a split ring helical gear carried by said shaft, 10 a closure plate for said aperture, said plate having a plurality of marginal apertures, one of said apertures being circular and the remaining apertures being elongated, securing means passing through said apertures, a bearing carried by said plate, a driven shaft journaled in said bearing, and a helical pinion carried by the lower end of said driven shaft and adapted to mesh with said ring gear, said plate being adapted 15 to pivot about said circular aperture, whereby said pinion may be accurately adjusted relatively to said ring gear.

4. In an automobile, the combination of a casing having an opening therein, a drive shaft within said casing and having a 25 clutch spring thereon, a sleeve surrounding said shaft and having a flange against which said spring normally bears, a ring gear having a flange clamped between said spring and said first mentioned flange, a 30 plate closing the opening in said casing and having an angularly offset wall, a threaded sleeve passing through said wall, a nut screwed upon said sleeve and clamping said sleeve to said wall, a driven shaft passing through said sleeve, and a pinion carried 35 by said driven shaft and meshing with said ring gear.

In testimony that I claim the foregoing I have hereunto set my hand at Clintonville, in the county of Waupaca and State of Wisconsin.

THOMAS A. PATTERSON.
